(57) **CLAIM**

The ornamental design for a cable clamp, as shown and described.

DESCRIPTION

FIG. 1 is a perspective view of a cable clamp showing my new design;

FIG. 2 is a left side elevational view of the present invention; FIG. 3 is a right side elevational view of the present invention;

FIG. 4 is a front elevational view of the present invention; FIG. 5 is a rear elevational view of the present invention; FIG. 6 is a top plan view of the present invention; and, FIG. 7 is a bottom plan view of the present invention.

The structures shown in broken lines form no part of the claimed invention.

The broken lines are for illustrative purposes only and form no part of the claimed design.
